DESIGN FOR A STOCKING

Tade Styka, New York, N. Y.

Application October 10, 1939, Serial No. 87,612

Term of patent 3½ years

To all whom it may concern:

Be it known that I, Tade Styka, a citizen of Poland and residing at New York city, county and State of New York, have invented a new, original, and ornamental Design for a Stocking, of which the following is a specification, reference being had to the accompanying drawing, forming part thereof.

Fig. 1 is a rear view of a stocking showing my new design.

Fig. 2 is a perspective view thereof.

I claim:

The ornamental design for a stocking, as shown.

TADE STYKA.
